WEB CUTTING AND FOLDING MECHANISM
FOR PRINTING MACHINES

Adolph M. Zuckerman, New York, N. Y., and Herman P. Clauberg, Hasbrouck Heights, N. J., assignors to R. Hoe & Co., Inc., New York, N. Y., a corporation of New York

Application November 19, 1941, Serial No. 419,778

20 Claims. (Cl. 270—6)

This invention relates to printing machines, and more particularly to improved web cutting and folding mechanism therefor.

In the operation of printing machines employed for printing magazines or like products, it is sometimes desirable to arrange to cut the printed web to form products of different sizes and to accurately fold them. This frequently requires difficult readjustment of the machine components in order to prepare the machine for cutting and folding the products of the selected size.

Cutting and folding mechanisms have been generally classified in two groups, the fixed size sheet type and the variable size sheet type. The fixed size sheet mechanism can be run at relatively high speed and is highly efficient, but of course no change in the length of sheet cut off is possible. The variable size sheet mechanism, however, will produce sheets of varying lengths, but this type of mechanism cannot be run at such high speed as the fixed size sheet mechanism, and consequently is less efficient.

There has been developed in the art, printing machines having cutting and folding mechanisms for producing products of different sizes by providing separate pairs of cooperating cutting cylinders, each pair cooperating to cut a product of a definite size. The pairs of cooperating cutting cylinders are mounted for movement transversely of the direction of the web run, so that each selected pair of cylinders may be located in the web path to cut sheets of the selected size. If sheets of a different size are required, then the support for the cutting cylinders is moved to locate another pair of cooperating cutting cylinders of a different size in the web path to cut the web into sheets of the required size.

There has also been recently developed in the art, a web cutting mechanism which has separate sets of fixed cooperable cutting cylinders that are located in the web path, and the mechanism is constructed and arranged so that when products of one size are to be cut, one set of cooperable cutting cylinders is rendered operative, and when sheets of a different size are to be cut, the other set of cooperable cutting cylinders operate to cut the sheet of the required size.

This invention contemplates the provision of an improved cutting and folding mechanism for use in rotary printing machines, and an object thereof is to so construct and arrange the mechanism that sheets of different sizes are cut and accurately folded by components of a common cutting mechanism and a common folding mechanism.

Another object of this invention is to provide for use in a printing machine, improved cutting and folding devices in which a common cutting mechanism is operable at a given speed to cut sheets of different lengths, and a common folding mechanism is operable at one speed to accurately fold sheets of one length and operable at another speed to accurately fold sheets of a different length.

10 A further object of this invention is to provide, for use in a printing machine, improved cutting and folding devices in which a common cutting mechanism is operable at a given speed to cut sheets of different lengths, and a common folding mechanism operable at one speed to fold sheets of one length and operable at a different speed to fold sheets of another length, and a delivery mechanism for delivering all the products away from the folding mechanism in one direction, or 15 to deliver certain of the products away from the folder in one direction, and the remaining products in the opposed direction.

20 A specific object of this invention is to provide, for use in printing machines, an improved web cutting and folding mechanism incorporating a rotary cutter adapted to cut first products of a given length and to cut second products of lesser length, a rotary folding cylinder, and means to drive the folding cylinder at approximately the 25 peripheral speed of the rotary cutter to fold the first products, and also at a high speed to fold the second products.

25 A more specific object of this invention is to provide in a web printing machine, a form cylinder arranged to receive printing plates to print a plurality of first products successively during each cylinder revolution, and alternatively to print a large number of smaller products successively during each cylinder revolution, a cutting mechanism adapted to cut the web into first products of a given length, and alternatively to cut the web into smaller products at the speed they are 30 printed by the form cylinder, and a folding machine adapted to be driven at a speed corresponding with that of the form cylinder to fold the first products, and at a faster speed to fold the smaller products.

35 It is also an object of this invention to provide, for use in printing machines, cutting and folding mechanisms of generally improved construction, whereby the device will be simple, durable, and relatively inexpensive in construction, as well as 40 convenient, practicable, serviceable and efficient in its use.

45 50 55 With the foregoing and other objects in view,

which will appear as the description proceeds, the invention resides in the combination and arrangement of parts and in the details of construction hereinafter described and claimed, it being understood that various changes in form, proportion and minor details of construction may be made within the scope of the claims without departing from the spirit or sacrificing any advantages of the invention.

For a complete disclosure of invention, a detailed description thereof will now be given in connection with the accompanying drawings forming a part of the specification, wherein:

Figure 1 is a diagrammatic side elevation of a printing machine which incorporates the improved cutting and folding mechanism.

Figure 2 is a diagrammatic end view.

Figure 3 is an enlarged fragmental end view of the improved folder.

Figure 4 is an elevation of the tucking blade cylinder, depicting the short gripper fingers employed in handling the larger product, the view being seen in the direction indicated by the arrows 4-4 in Figure 3.

Figure 5 is a plan view of the delivery cylinders, the view being seen in the direction indicated by the arrow 5 in Figure 3.

Figure 6 is an end view of the cutting cylinders, their shafts being shown in section, and the cylinder components being arranged for cutting four products per cylinder revolution.

Figure 7 is an end view of the tucking blade cylinder, the cylinder being provided with long gripper fingers for handling the shorter products.

Figure 8 is an end view of the delivery cylinders, their shafts being shown in section, and the components of the cylinders being arranged to deliver products alternatively in opposed directions.

Figure 9 is an elevation of the tucking blade cylinder, similar to Figure 4, except the longer gripper fingers, depicted in Figure 7, are employed for handling the smaller products, the view being seen in the direction indicated by the arrows 9-9 of Figure 7.

Figure 10 is a plan view of the delivery cylinders, similar to Figure 5, but showing gripper fingers on both cylinders.

Referring to the drawings, in which similar reference characters designate corresponding parts, there is depicted a frame 12 of a rotary printing machine, and the frame 13 of its folder. The printing machine includes any preferred number of perfecting printing units having preferably superposed printing couples, as best seen in Figure 1. Although the arrangement in which superposed printing couples are provided is a preferred arrangement, it is to be understood, of course, that the printing couples may be otherwise disposed if desired. Each couple includes an impression cylinder 15, which is rotatably supported in the machine frame 12, in conformity with the usual practice. A plate or form cylinder 16 cooperably engages each impression cylinder 15, and ink is supplied to each plate cylinder from a fountain 17, of usual construction, through an interposed ink distributing mechanism 18. If preferred, however, ink may be supplied to a cylinder of the ink distributing mechanism by an ink rail of usual construction, which arrangement is well understood by those skilled in the art. The plate or form cylinders 16 are arranged to support either six or eight plates around each cylinder, depending upon the size of the product.

to be produced, as will be fully explained hereinafter.

As seen in Figure 1, a web W is guided to and through the printing couples by guide rollers 20, and after passing through the printing couples, the web is guided by rollers 21 to a drag or propeller roller 22, with which slitter discs 23 cooperate to cut the web into ribbons WR. The ribbons WR are passed over turner bars 25, as best seen in Figure 2, and then these ribbons are guided around rollers 26 to associating rollers 27. After the ribbons WR are associated by the rollers 27, these associated ribbons are led to feeding rollers 28 and 30 of the folder. The feeding rollers 28 and 30 are rotatably mounted in conventional bearings, not shown, supported by the folder frame 13, and these rollers are geared together for simultaneous rotation in the usual manner which is well understood by those skilled in the art, consequently the gears have not been illustrated. After passing through the feed rollers 28 and 30, the ribbons WR are carried between the cutting cylinders 31 and 32, which are rotatably mounted in the usual manner in bearings supported by the folder frame 13. The cutting cylinders 31 and 32 cut the ribbons into sheets, and the sheets are carried through the folder to the delivery mechanism, as will be more fully explained hereinafter.

The cutting cylinders are geared together for simultaneous rotation, in conformity with the usual practice in the art, and the shaft of the cutting cylinder 32 has a bevel gear 33 rigidly secured thereto. This gear meshes with a bevel pinion 35 carried by a horizontal shaft 36 which is rotatably supported in bearings in the folder frame 13. A bevel pinion 37 is secured to the outer terminal of the shaft 36, and this pinion meshes with a similar bevel pinion 38 carried by a vertical shaft 40, which is rotatably supported in bearings in the folder frame 13. At the lower terminal of the vertical shaft 40 there is secured a bevel pinion 41 which meshes with a similar pinion 42 carried by a horizontal drive shaft 43, which may be driven from any suitable source of power, not shown, in conformity with the usual practice.

Gears 44 and 45 are secured to the intermediate portion of the horizontal shaft 36, and the gear 44 meshes with a similar gear 46 which rotates with a horizontally-disposed shaft 47 rotatably supported in bearings in the folder frame 13. A gear 48 rotates with the shaft 47, and the gears 46 and 48 are carried by and rigidly secured to a sleeve or hub 50 which is slidably mounted on the shaft 47, but is splined to this shaft to prevent rotation of the gears 46 and 48 relative to the shaft. The hub or sleeve 50 is provided with an annular groove 51 for the reception of rollers 52 carried at the bifurcated terminal 53 of a lever 55, which is fulcrumed, as indicated at 56, to a bracket 57 carried by the folder frame 13. By this arrangement, when the lever 55 is swung about its fulcrum 56, the gears 46 and 48 are slid along the shaft 47 so that the gear 46 is moved from meshing engagement with the gear 44, for a purpose to be hereinafter disclosed.

A bevel pinion 60 is secured to one terminal of the shaft 47, and this pinion meshes with a bevel gear 61 carried by shaft 62 of a jaw cylinder 63. The jaw cylinder 63 is geared to a tucking blade cylinder 65, in conformity with the usual practice, so that the cylinders 63 and 65 rotate in unison. By this arrangement, the jaw

cylinder 63 and tucking blade cylinder 65 are driven from the shaft 47 through the bevel pinion 60 and the bevel gear 61.

The tucking blade cylinder 65 is provided with gripper shafts 66, which are mounted for rocking movement in the tucking blade cylinder 65, in conformity with the usual practice. Each gripper shaft 66 supports a plurality of gripper fingers which are detachably secured to the shaft. When the machine is adjusted to handle products of one size, each shaft 66 supports relatively short gripper fingers 67, as best shown in Figures 3 and 4. If products of a smaller size are to be handled by the machine, then the short gripper fingers 67 are not used, but they may remain in place, while longer gripper fingers 68, best shown in Figures 7 and 9, are secured to this shaft. Any suitable construction may be employed to detachably secure the gripper fingers to the shafts 66, but a preferred construction is depicted in Figures 3, 4, 7 and 9. In this construction, supporting blocks 70 are carried at spaced intervals along each shaft 66, and these blocks are provided with threaded apertures 71 (best seen in Figure 4) for the reception of securing screws 72 which extend through apertures formed in the gripper fingers 67 and 68 to rigidly secure each finger to its supporting block 70. In order to remove any gripper finger, it is necessary only to remove the securing screws 72 from the selected gripper finger and supporting block 70.

The tucking blade cylinder 65 is provided with three tucking blades 73, which are operably supported by the cylinder 65, so that they may be projected, at the proper time, radially beyond the peripheral portion of the tucking blade cylinder. The tucking arrangement is of conventional construction which is well understood by those skilled in the art, therefore it is only diagrammatically illustrated in the drawings of this application. The gripper shafts 66 are rocked or oscillated to actuate the gripper fingers by the conventional cam and roller mechanism, not shown, but which is well understood by those skilled in the art. The jaw cylinder 63 is provided with three sets of folding jaws 75 of usual construction, and the movable jaws are opened and closed by rock shafts 76, which are actuated by the conventional cam and roller mechanism that is well understood by those skilled in the art, consequently they are not illustrated in the drawings of this application. These jaws coact with the tucking blades 73 to receive and fold products in conformity with the usual practice.

As seen in Figure 3, a spring pressed feed roller 77 yieldingly engages the peripheral portion of the jaw cylinder 63, and a similar spring pressed feed roller 78 yieldingly engages a fixed feed roller 80 to feed products from the jaw cylinder 63 to the delivery mechanism to be hereinafter described.

Coacting delivery cylinders 81 and 82 are located below the feed rollers 78 and 80, and these delivery cylinders are operably supported by shafts 63 and 85 which are rotatably mounted in bearings in the folder frame 13. The delivery cylinder 81 is provided with four rock shafts 86 to which gripper finger supporting blocks 87 are rigidly secured. In a phase of the operation of the machine, to be hereinafter described, a gripper finger 88 is detachably secured to each block 87 by bolts or screws 90, so that four products may be delivered during each revolution of the 75

delivery cylinder, as best shown in Figure 8. The coacting delivery cylinder 82 is provided with two diametrically opposed rock shafts 91 which have gripper fingers supporting blocks 92 rigidly secured thereto. During a phase of the operation of the machine, a gripper finger 88 is secured to each block 92, as best shown in Figure 8, and during another phase of operation of the machine, the two gripper fingers are removed from the blocks 92, as will be fully explained hereinafter. Each rock shaft 86 or 91 has a rocker arm 93 secured to a terminal thereof, and each arm 93 is provided with a cam roller 95 to be engaged by a cam of usual construction, not shown, to open and close the gripper fingers in proper timed relation to the feeding products, in conformity with the usual practice. The gripper fingers 88 are normally held in their closed or gripper position by helical extension springs 96, of usual construction, as shown in Figure 8. The products are gripped by the gripper fingers 88 and are carried around the delivery cylinders 81 and 82 until they are engaged by stop members or strippers 97 and 98, which strip the products from the cylinders and deposit them on conveyer belts 100 and 101, of usual construction. The conveyer belt 100 is supported by rollers 102, and this belt is driven to convey products to the left from the delivery cylinder 81, as viewed in Figure 3. The delivery belt 101 is supported by rollers 103, and it is driven to deliver products to the right from the delivery cylinder 82, as viewed in Figure 3.

Cut sheets are guided from the cutting cylinders 31 and 32 by vertical guide members 104, and the sheets are held in proper relation to the peripheral portion of the tucking blade cylinder 65 by arcuate guide members 105, of conventional construction, that are arranged in concentric relation to the tucking blade cylinder 65. Similar guides 106 and 107 are arranged in concentric relation to the jaw cylinder 63. A stripper and guide member 108 is supported to strip the leading edges of the products from the jaw cylinder 63 and guide the products to the feed rollers 78 and 80.

The peripheral portion of the cutting cylinder 31 (as seen in Figure 6) is provided with six radial slots 110 for the reception of cutting knives 111 and the conventional knife supporting members or cheek woods 112. The slots 110 are arranged so that three cutting knives 111 may be supported therein, one hundred twenty degrees apart, when one type of product is being cut, or four cutting knives may be supported therein, ninety degrees apart, when a different size product is being cut, as will be more fully explained hereinafter.

The peripheral portion of the cutting cylinder 32 is also provided with six slots 113, which receive the conventional cutting rubbers or abutments 115. When three cutting knives are employed in the knife cylinder 31, then three abutments 115 are positioned in the slots 113, one hundred twenty degrees apart, or if four knives are employed, then four abutments are supported in the slots 113, ninety degrees apart.

In operation, the machine is constructed and arranged to print, cut, fold and deliver products of a given size and also products of a larger size. When the large products are to be produced, three cutting knives 111 are operably positioned in the cutting or knife cylinder 31, and three coacting cutting abutments 115 are positioned in the cutting cylinder 32, so that for each revolu-

tion of the cutting cylinders, three sheets or products are cut.

When this large product is to be printed, six plates may be arranged around each impression cylinder 15 of the printing unit or units. The web W is guided through the printing units, as hereinbefore disclosed, and after the web receives its impressions, it is slit into ribbons WR, and these ribbons are guided over the turner bars 25 and around rollers 26 to their associating rollers 27, and then to the feed rollers 28 and 30. These feed rollers may be driven from any suitable source of power, and in the arrangement depicted in Figure 3, an idler gear 116 is operably interposed between the roller 29 and the cutting cylinder 32, so that the gear 116 meshes with a gear, not shown, which is rotatable with the feed roller 30, and also with a gear, not shown, that rotates with the cutting cylinder 32. After the ribbons WR pass the feed rollers 28 and 30, they are engaged by the cutting knives 111 and cut into three sheets for each revolution of the printing cylinders 15 and 16 and the cutting cylinders 31 and 32. The cut sheets are then guided by the guide members 104, and they are propelled through the guide members 104 to the tucking blade cylinder by feed rollers 117 and 118, which are driven by an idler gear 120 that meshes with a gear, not shown, which rotates with the feed roller 118, and a gear, not shown, that rotates with the tucking blade cylinder 65. At the lower terminal of the guide members 104, the sheets are taken by the short gripper fingers 67 of the tucking blade cylinder 65 and conveyed around the tucking blade cylinder to the jaw cylinder 63. The gripper fingers 67 are so located on the cylinder 65 that when each sheet is taken by a gripper finger, its intermediate portion overlies a tucking blade 73. When the intermediate portion of each sheet reaches the bite of the tucking blade cylinder 65 and the jaw cylinder 63, a tucking blade 73 moves radially towards the jaw cylinder 63 and tucks the intermediate portion of the sheet into the open folding jaws 75. Each sheet is two pages long, so that when it is folded by the cooperable engagement of the tucking blade 73 with the folding jaws 75, the sheet is folded intermediate its terminals, in order to dispose a page at each side of the fold. The folded sheet is then conveyed around the jaw cylinder 63 by the folding jaws 75, and the trailing edge of the sheet is retained in proper relation to the cylinder by the guide members 106 and 107. The folded sheet is then engaged by the feed roller 77 and released from the jaws 75, and finally directed and conveyed by the guide member 108 and feed rollers 78 and 80 to the delivery cylinders 81 and 32. When the large size products are being produced and only three cutting knives are employed in the cutting cylinder 31, the folded leading edge of each folded sheet is gripped by gripper fingers 88, carried by the delivery cylinder 81, and conveyed to the conveyor belt 100. Each product when released from the gripper fingers is stripped from the delivery cylinder 81 by the stripper member 97, in conformity with the usual practice, and then the product is conveyed to the left from the delivery cylinder 81, as seen in Figure 3.

When these large size products are to be produced, the lever 55, which manipulates the change speed gear mechanism, is moved to the position shown in full line in Figure 3, so that the gears 44 and 46 are in mesh. In this drive relationship, the tucking blade cylinder 65 and

jaw cylinder 63 are driven at the same peripheral speed as the printing and cutting cylinders, and all the products are delivered by the delivery cylinder 81 and conveyor belt 100 to the left, as hereinbefore stated.

When the smaller products are to be produced, the plate cylinders 16 of the printing unit have eight plates arranged therearound and two sets of forms are employed, for a purpose to be disclosed hereinafter. In this arrangement, four cutting knives 111 are positioned in the cutting cylinder 31, and four cooperating cutting abutments 115 are positioned in the cutting cylinder 32, so that for each revolution of the cutting cylinders, four sheets are cut. In order to receive the smaller products, the short gripper fingers 67 are removed from the tucking blade cylinder 65 and the longer gripper fingers 68 are secured thereto. Because the short sheets do not extend one-third around the cylinder, and since the intermediate portion of the short sheets must overlie the tucking blade 73, the longer gripper fingers 68 extend farther around the periphery of the tucking blade cylinder 65 in order to correctly position the sheets in relation to the tucking blades. Prior to making the short-sheet run, the gear shift lever 55 is shifted to the dotted line position, shown in Figure 3, so that the gears 45 and 48 are in mesh. This drives the folding cylinders 63 and 65 at an increased peripheral speed, so that the three sets of long gripper fingers 68 carried by the tucking blade 65 can properly receive the short sheets and convey them to their folding destination. In this four-sheet run, two of the gripper fingers 68 are removed from the delivery cylinder 81 and then secured to the delivery cylinder 82, as shown in Figure 8, so that certain of the products are deposited on the delivery belt 103 and conveyed to the left, as viewed in Figure 3, and the alternate products are deposited on the delivery belt 101 and conveyed to the right, as viewed in this figure.

Inasmuch as two sets of forms have been employed, products printed from one set are conveyed to the left by the conveyor belt 100, and products printed from the other are conveyed to the right by the conveyor belt 101, as viewed in Figure 3, but if preferred, a single set of forms may be employed on the plate cylinders 16, and then four gripper fingers 68 may be employed on the delivery cylinder 81, so that all products are delivered to the left, as viewed in Figure 3.

With this arrangement, different size products may be produced by the same instrumentalities, by simply making minor adjustments and changes in the disposition of certain operating components. Furthermore, the resulting products may be delivered to a common destination, or, if desired, to different destinations, in conformity with the size and character of the product being produced.

It will be understood that the invention herein disclosed may be embodied in other specific forms without departing from the spirit or essential attributes thereof, and it is therefore desired that the present embodiment be considered in all respects as illustrative and not restrictive.

What we claim is:

1. In a web cutting and folding mechanism for printing machines, a rotary cutter adapted to cut first products of a given length and to cut second products of lesser length, a rotary folding cylinder, and means to drive the folding cylinder at approximately the peripheral speed of the ro-

tary cutter to fold the first products, and at a higher speed to fold the second products.

2. In a web cutting and folding mechanism for printing machines, cooperable cutting cylinders adapted to cut first products of a given length and to cut second products of lesser length, cooperable folding cylinders, and means to drive the folding cylinders at approximately the peripheral speed of the cutting cylinders to hold the first products, and at a higher speed to fold the second products.

3. In a web cutting and folding mechanism for printing machines, cooperable cutting cylinders adapted to cut first products of given length and to cut second products of lesser length, cooperable folding cylinders, means to drive the folding cylinders at approximately the peripheral speed of the cutting cylinders to fold the first products, and at a higher speed to fold the second products, driven conveyers, and delivery cylinders operably interposed between the folding cylinders and the conveyers to deliver the folded products to the conveyers.

4. In a web cutting and folding mechanism for printing machines, cooperable cutting cylinders adapted to cut first products of a given length and to cut second products of lesser length, cooperable folding cylinders, means to drive the folding cylinders at approximately the peripheral speed of the cutting cylinders to fold the first products, and at a higher speed to fold the second products, driven conveyers, delivery cylinders operably interposed between the folding cylinders and the conveyers to deliver the folded products to the conveyers, and feed rollers operably interposed between the folding cylinders and the delivery cylinders to feed folded products from the folding cylinders to the delivery cylinders.

5. In a web cutting and folding mechanism for printing machines, cooperable cutting cylinders adapted to cut first products of a given length and to cut second products of lesser length, cooperable folding cylinders, means to drive the folding cylinders at approximately the peripheral speed of the cutting cylinders to fold the first products, and at a higher speed to fold the second products, two driven conveyers, one conveyor adapted to convey products in one direction away from the folder and the other to convey other products in opposed direction away from the folder, cooperable delivery cylinders operably interposed between the folding cylinders and the conveyers and adapted to deliver the folded first products from the folding cylinders to one conveyor and the folded second products to both conveyers.

6. In a web cutting and folding mechanism for printing machines cooperable cutting cylinders adapted to cut first products of given length and to cut second products of lesser length, cooperable folding cylinders, means to drive the folding cylinders at approximately the peripheral speed of the cutting cylinders to fold the first products, and at a higher speed to fold the second products, two driven conveyers, one conveyor adapted to convey products in one direction away from the folder and the other to convey other products in opposed direction away from the folder and cooperable delivery cylinders operably interposed between the folding cylinders and the conveyers and adapted to deliver folded products from the folding cylinders to one conveyor and alternate products to the other conveyor, or alternatively to deliver all products to one conveyor.

7. In a web cutting and folding mechanism for printing machines, cooperable cutting cylinders adapted to cut first products of relatively long length and to cut second products of lesser length, cooperable first and second folding cylinders, means to drive the folding cylinders at approximately the peripheral speed of the cutting cylinders to fold the first products, and at a higher speed to fold the second products relatively short gripper fingers removably secured to the first folding cylinder to receive the relatively long first products, and relatively long gripper fingers removably secured to the first folding cylinder to receive the relatively short second products.

8. In a web cutting and folding mechanism for printing machines, cooperable cutting cylinders adapted to cut first products of relatively long length and to cut second products of lesser length, cooperable first and second folding cylinders, means to drive the folding cylinders at approximately the peripheral speed of the cutting cylinders to fold the first products, and at a higher speed to fold the second products, tucking blades carried by the first folding cylinder, folding jaws carried by the second folding cylinder to cooperably receive the tucking blades to fold the cut products intermediate their terminals, relatively short gripper fingers removably secured to the first folding cylinder to receive the relatively long first products to position the intermediate portion of each product over a tucking blade, and relatively long gripper fingers removably secured to the first folding cylinder to receive the relatively short second products to position the intermediate portion of each product over a tucking blade.

9. In a web cutting and folding mechanism for printing machines, cooperable cutting cylinders adapted to cut first products of relatively long length and to cut second products of lesser length, cooperable first and second folding cylinders, means to drive the folding cylinders at approximately the peripheral speed of the cutting cylinders to fold the first products, and at a higher speed to fold the second products, guide members interposed between the cutting cylinders and the first folding cylinder to convey cut products from the cutting cylinders to the first folding cylinder, relatively short gripper fingers removably secured to the first folding cylinder to receive the relatively long first products from the guide members, and relatively long gripper fingers removably secured to the first folding cylinder to receive the relatively short second products from the guide members.

10. In a web cutting and folding mechanism for printing machines, cooperable cutting cylinders adapted to cut first products of relatively long length and to cut second products of lesser length cooperable first and second folding cylinders, means to drive the folding cylinders at approximately the peripheral speed of the cutting cylinders to fold the first products, and at a higher speed to fold the second products, radially movable tucking blades carried by the first folding cylinder, folding jaws carried by the second folding cylinder to cooperably engage the tucking blades to fold the cut products intermediate their terminals, guide members interposed between the cutting cylinders and the first folding cylinder to convey cut products from the cutting cylinders to the first folding cylinder, relatively short gripper fingers removably secured to the first folding cylinder to receive the relatively

long first products from the guide members to position the intermediate portion of each product over a tucking blade, and relatively long gripper fingers removably secured to the first folding cylinder to receive the relatively short second products from the guide members to position the intermediate portion of each product over a tucking blade.

11. In a web cutting and folding mechanism for printing machines, a rotary cutter adapted to cut first products of a given length and to cut second products of lesser length, a rotary folding cylinder, a driven shaft, a speed change mechanism operably interposed between the folding cylinder and the driven shaft and adjustable to produce two speed ratios to drive the folding cylinder at approximately the peripheral speed of the rotary cutter to fold the first products, and at a higher speed to fold the second products.

12. In a web cutting and folding mechanism for printing machines, cooperable cutting cylinders adapted to cut first products of a given length and to cut second products of lesser length, cooperable folding cylinders, a driven shaft, a speed change mechanism operably interposed between the folding cylinders and the driven shaft and adjustable to produce two speed ratios to drive the folding cylinders at approximately the peripheral speed of the rotary cutting cylinders to fold the first products, and at a higher speed to fold the second products.

13. In a web cutting and folding mechanism for printing machines, a driven shaft, cooperable cutting cylinders driven from the driven shaft and adapted to cut first products of a given length and to cut second products of lesser length, separate first gears of different diameters driven from the driven shaft, cooperable folding cylinders, a second shaft operably connected with the folding cylinders, and separate second gears of different diameters rotatable with the second shaft and slidable thereon so that each gear selectively engages one of the first gears to drive the folding cylinders at approximately the peripheral speed of the cutting cylinders to fold the first products, and at a higher speed to fold the second products.

14. In a web cutting and folding mechanism for printing machines, a driven shaft, a first shaft driven by the driven shaft, cooperable cutting cylinders driven by the first shaft and adapted to cut first products of a given length and to cut second products of lesser length, separate gears of different diameters rotatable with the first shaft, cooperable folding cylinders, a second shaft operably connected with the folding cylinders, separate gears of different diameters rotatable with the second shaft and slidable thereon so that one of the second gears selectively engages a first gear to drive the folding cylinders at approximately the peripheral speed of the cutting cylinders to fold the first products, and at a higher speed to fold the second products.

15. In a web cutting and folding mechanism for printing machines, a driven shaft, a first shaft driven by the driven shaft, cooperable cutting cylinders driven by the first shaft and adapted to cut first products of a given length and to cut second products of lesser length, separate gears of different diameters rotatable with the first shaft, cooperable folding cylinders, a second shaft operably connected with the folding cylinders, a sleeve slidable on the second shaft

and secured against rotation relative to this shaft, separate gears of different diameters rotatable with this sleeve and slidable therewith, means for slidably moving the sleeve on the shaft to selectively move one of the second gears into meshing engagement with a first gear to drive the folding cylinders at approximately the peripheral speed of the cutting cylinders to fold the first products and to move one of the second gears into meshing engagement with another first gear to drive the folding cylinders at a higher speed to fold the second products.

16. In a web cutting and folding mechanism for printing machines, a rotary cutter, cutting members removably secured to the cutter in different numbers and in different locations and adapted when employed in a given number and in given locations to cut first products of a given length and when employed in another number and other locations to cut second products of a lesser length, a rotary folding cylinder, and means to drive the folding cylinder at approximately the peripheral speed of the rotary cutter to fold the first products, and at a higher speed to fold the second products.

17. In a web cutting and folding mechanism for printing machines, two cooperable cutting cylinders, cutting abutments removably secured to one cylinder in different numbers and in different locations, cutting knives operably supported by the other cylinder in different numbers and in different locations to cooperably engage the cutting abutments, the cutting abutments and knives adapted when employed in a given number and in given locations to cut first products of a given length and when employed in another number and in other locations to cut second products of lesser length, cooperable rotary folding cylinders, and means to drive the folding cylinders at approximately the peripheral speed of the cutting cylinders to fold the first products, and at a higher speed to fold the second products.

18. In a web printing machine, a form cylinder arranged to receive a given number of printing plates therearound and to print therefrom a plurality of first products successively during each cylinder revolution and alternatively to receive a larger number of smaller printing plates therearound to print therefrom a larger number of smaller products successively during each cylinder revolution, a cutting mechanism adapted to cut the web into the first products and alternatively into the smaller products at the speed they are printed by the form cylinder, and a folding mechanism adapted to be driven at a speed corresponding with that of the form cylinder to fold the first products, and at a faster speed to fold the smaller products.

19. In a web printing machine, a form cylinder arranged to receive a given number of printing plates therearound and to print therefrom a plurality of first products successively during each cylinder revolution and alternatively to receive a larger number of smaller printing plates therearound to print therefrom a larger number of smaller products successively during each cylinder revolution, cooperable cutting cylinders adapted to cut the web into the first products and alternatively into the smaller products at the speed they are printed by the form cylinder, cooperable folding cylinders, and means to drive the folding cylinders at approximately the peripheral speed of the form cylinder and cutting cylinders to fold the first products, and at a higher speed to fold the smaller products.

20. In a web printing machine, a form cylinder arranged to receive a number of printing plates therearound and to print therefrom a plurality of first products successively during each cylinder revolution and alternatively to receive a larger number of smaller printing plates therearound to print therefrom a larger number of smaller products successively during each cylinder revolution, cooperable cutting cylinders adapted to cut the web into the first products and 10 alternatively into the smaller products, cooper-

able folding cylinders, a drive shaft, a speed change mechanism operably interposed between the drive shaft and folding cylinders and adjustable to produce two speed ratios to drive the folding cylinders at approximately the peripheral speed of the cutting cylinders to fold the first products, and at a higher speed to fold the smaller products.
